(57) **CLAIM**

The ornamental design for endcaps for a vibrating fitness roller, as shown and described.

DESCRIPTION

FIG. 1 is a front perspective view of endcaps for vibrating fitness roller of the present design;

FIG. 2 is a rear perspective view thereof;

FIG. 3 is a top view thereof, the bottom view being a mirror image thereof;

FIG. 4 is a left side view thereof, the bottom view being a mirror image thereof;

FIG. 5 is a front view thereof; and,

FIG. 6 is a rear view thereof.

The broken lines in the drawings are for the purposes of illustrating portions of the endcaps for vibrating fitness roller, which form no part of the claimed design.

1 Claim, 5 Drawing Sheets
